[57] CLAIM

The ornamental design for a light for video camera, as shown and described.

DESCRIPTION

FIG. 1 is a perspective view of a first embodiment of a light for video camera showing my new design;

FIG. 2 is a top plan view thereof;

FIG. 3 is a front elevational view thereof;

FIG. 4 is a bottom plan view thereof;

FIG. 5 is a right side elevational view thereof, the left side elevational view being the mirror image; and

FIG. 6 is a rear elevational view thereof.

FIG. 7 is a perspective view of a second embodiment of a light for video camera showing my new design;

FIG. 8 is a top plan view thereof;

FIG. 9 is a front elevational view thereof;

FIG. 10 is a bottom plan view thereof;

FIG. 11 is a right side elevational view thereof, the left side elevational view being the mirror image; and,

FIG. 12 is a rear elevational view thereof.
